Dr. J. W. Dorn

ATTORNEY

UNITED STATES PATENT OFFICE.

GEORGE NORMAN, OF SMALL HEATH, BIRMINGHAM, ENGLAND, ASSIGNOR TO THE BIRMINGHAM SMALL ARMS COMPANY LIMITED, OF BIRMINGHAM, ENGLAND.

SMALL ARM.

Application filed November 17, 1926, Serial No. 148,956, and in Great Britain July 9, 1925.

This invention relates to improvements in small arms and more particularly to trigger guards of the kind which are also adapted to constitute means for attachment of the gun stock to the breech end of the gun, and has for its object to provide an improved construction and arrangement of trigger guard and means adapted to permit of the ready attachment or detachment of same without the use of tools of any kind.

According to the invention a trigger guard is provided which comprises a plate having at its front end a hook formation arranged to engage with a lug or projection fitted to or formed on the underside of the forward part of the breech body or receiver, and its rear end, which is adapted to surround the trigger, is provided with a hook adapted to be engaged by a lever or catch mounted on the under side of the breech body near the rear end thereof, and upon which the trigger is pivotally supported, the trigger providing means, when moved in a forward direction, for releasing the lever or catch from engagement with the trigger guard. The invention also contemplates the utilization of the trigger spring to effect the locking movement of the trigger guard lever or catch. Means are also provided whereby the trigger guard lever or catch is held or locked in its engaged position, to prevent inadvertent movement, due to jarring, as for instance when the gun is fired.

The invention will be described with reference to the accompanying drawings, in which:—

Figure 1 is a view, partly in section and partly in elevation, of a small arm provided with a trigger guard constructed in accordance with and embodying the features of this invention.

Figures 2 and 2^a are, respectively a side elevation and a plan view of the trigger guard.

Figures 3 and 3^a are, respectively a side and front elevation of the trigger guard catch.

Figures 4 and 4^a are, respectively, a side and front elevation of the trigger.

Figures 5, 5^a and 5^b are, respectively a side and front elevation and a plan view of the trigger guard attachment stud.

According to one practical embodiment of this invention as illustrated in the accompanying drawings, the trigger guard 1 is

provided at its forward end with a hook-shaped formation in which a longitudinal slot or gap 2 is formed thus providing two arms 3 adapted to engage with a T shaped stud 4 mounted in the under side of the forward end of the breech body or receiver 5, the said stud being arranged to lie in a hole formed in the fore end stock 6. In the plate forming the forward part of the trigger guard is formed a rectangular slot 7 adapted to embrace the magazine 8. The rear end of the trigger guard is shaped in the usual manner to surround the trigger 9, and is further provided with a vertically disposed attachment hook or projection 10 adapted to engage with a spring controlled lever or catch 11 carried on the underside of the rear end of the breech body 5, whereby the trigger guard 1 is held in position, and secures the stock 6 to the breech body of the gun, without the use of the usual attachment screws.

In a preferred construction the trigger guard catch 11 comprises a depending lever provided at its lower end with a nose part 12 for engagement with the hook 10 on the trigger guard 1, and near its centre with a pair of lugs 13, between which the trigger 9 is carried on a pivot pin 14. To the trigger 1, at a position above its pivot centre and almost in alignment with the pivot centre 15 of the trigger guard catch 11, is connected a trigger bar 16 or other means for actuating the sear 17, of the trigger mechanism. The trigger spring 18, which is mounted on the under side of the breech body 5, is so arranged that its free end impinges against the trigger 9 at a point above its pivot 14, thus keeping the upper part of the trigger in contact with the front face of the trigger guard catch 11, and, since the spring exerts pressure below the pivot centre 15 of the catch 11, it tends to move the catch 11 into engagement with the attachment hook 10 on the said trigger guard.

In order to limit or control the movement of the trigger guard catch 11 toward the attachment hook 10 of the trigger guard and to provide means whereby it may be held or locked in engagement with said hook, the upper end of said catch is extended rearwardly and provided with upwardly extending lugs 19 which protrude through a slot in the underside of the breech body, and are adapted to be engaged by an end cap 20

or like device mounted on the outer or rear end of the breech body, such as the detachable end cap of an automatic gun, employed to hold the bolt mechanism return spring within the breech body.

It will be readily understood that, when it is desired to remove the trigger guard 1 in the process of stripping the gun, the end cap 20 is first removed thus permitting of the movement of the trigger guard catch 11 by a forward movement of the trigger 9, which being mounted on the said catch, moves the latter from engagement with the trigger guard and permits of its detachment.

15 The plate part of the trigger guard is preferably set or bent so that, when placed in position, it exerts an upward spring pressure on the gun stock, thus holding the latter in close contact with the breech body 5 20 of the gun.

Having fully described my invention, what I desire to claim and secure by Letters Patent is:—

1. A trigger guard for small arms, comprising a plate having at its front end a hook formation, a projection carried by the

underside of the breech body and engageable by said hook formation, said trigger guard having at its rear end a hook, a catch mounted on the underside of the breech body 30 and engageable with the rear end of the trigger guard, and a trigger pivoted on said catch.

2. A trigger guard for small arms, according to claim 1, wherein the pivot of the 35 trigger is so located on the catch that a forward movement of the trigger will release the catch from engagement with the rear end of the trigger guard.

3. A trigger guard for small arms, according to claim 1, wherein a spring associated with the trigger is adapted to effect the locking engagement of the catch with trigger guard.

4. In a firearm according to claim 1, an 45 end cap removably secured in the rear end of the breech body and wherein the trigger guard catch is provided with a lug or projection adapted to be engaged by the end cap, whereby the said catch is held in engagement with the trigger guard.

GEORGE NORMAN.
